UNITED STATES PATENT OFFICE

JOHN EDDY CHACE, OF ADAMSDALE, MASSACHUSETTS

BOTTLE CLOSURE

Application filed May 11, 1928. Serial No. 276,983.

This invention relates to bottle closures of the type disclosed in my co-pending application for United States Letters Patent Serial No. 177,147, filed March 21st, 1927, of which 5 co-pending application the present application forms a continuation, in part.

As set forth in my above mentioned co-pending application, the present invention relates to sanitary bottle closures of that kind 10 embodying a disk member adapted to be seated within the mouth of the bottle, and a cap member carrying the disk member and having a marginal rim or flange adapted to fit over the mouth of the bottle to effectively prevent entrance of dirt and other foreign 15 matter into the bottle and consequent contamination of the bottle contents.

More particularly, the present application 20 is directed to certain forms of bottle closures, of the above kind wherein the cap member has a flat top wall, and wherein means is provided for cooperation with said top wall to prevent nesting of the closures when a plurality of 25 the same are arranged in superimposed relation within the feed hopper of a bottle capping machine, and wherein the cap member and disk are so associated as to provide for efficient application of the closure to the 30 bottle.

A further object is to provide a bottle closure characterized as above, and so constituted as to provide for ready and economical manufacture.

The invention consists in the novel form, combination and arrangement of parts hereinafter more fully described, shown in the accompanying drawings and claimed.

In the drawings:—

Figure 1 is a bottom plan view of one form of sanitary bottle closure constructed in accordance with the present invention;

Figure 2 is a transverse sectional view thereof taken on line 2—2 of Figure 1;

Figure 3 is a view similar to Figure 1 of a slightly modified form of the closure shown in Figures 1 and 2;

Figure 4 is a section on line 4—4 of Figure 3;

Figure 5 is a view similar to Figure 3 show-

ing another form of bottle closure embodying the present invention;

Figure 6 is a section on line 6—6 of Figure 5;

Figure 7 is a bottom plan view of still another form of bottle closure embodying the present invention;

Figure 8 is a section on line 8—8 of Figure 7;

Figure 9 is a bottom plan view of yet another form of bottle closure embodying the present invention;

Figure 10 shows the closure of Figure 9, applied to the mouth of a milk bottle, the bottle being in vertical section, and the closure being in section on line 10—10 of Figure 9; and

Figure 11 is a fragmentary view partly in vertical section and partly in side elevation, showing a plurality of the present bottle closures arranged in superimposed relation within the feed hopper of a bottle filling and capping machine.

Referring more in detail to the drawings, the present bottle closure essentially embodies a cap member 5 having a normally flat top wall and provided with a depending rim 6, a closure disk 7 attached to the underside of said top wall, a circular part or ring 8 attached to the underside of and depending from the top wall of the cap member 5, said circular part or ring 8 being adapted to receive the pressure of a die in the application of the cap to a bottle as indicated at 9 in Figure 10 and having direct pressure contact with the margin of the closure disk 7 as indicated at 10. The ring or depending part 8 is therefore located above the marginal portion of the closure disk 7 in position to enable the die to effectively force the margin of the disk 7 into proper seating contact with the internal shoulder 11 usually provided in the mouth of the milk bottle 12.

As the top wall of the cap member 5 is normally flat the portion thereof within the ring 8 is in the same horizontal plane with the marginal portion of said top wall outwardly of the ring 8. The closure disk 7 is provided inwardly of its margin with a depending portion 13 located substantially in

the same horizontal plane with the lower edge of the rim 6 and adapted to rest upon the central portion of the top wall of the cap member 5 of another similar closure disposed therebeneath for preventing nesting of said closures. It is thus apparent that a plurality of the closures may be readily placed in superimposed relation within the feed hopper 14 of a bottle capping and filling machine as shown in Figure 11, with the lowermost closure readily displaceable from beneath those disposed thereabove under the action of the usual ejecting plunger 15. Unhampered feeding of the caps successively from the bottom of the hopper for application to successive bottles is thus effectively insured.

A relatively small spacer disk 16 may be secured between the central portions of the top wall of the cap member 5 and the closure disk 7 in spaced concentric relation to and within the ring 8, thus enabling the contact pressure of the capping die to be directly transmitted from the center of the top wall of the cap member 5 to the center of the closure disk 7, whereby the closure may be caused to dish downwardly to the form of Figure 10, upon application of the closure to the bottle. In this way, most efficient seating of the closure disk 7 within the mouth of the bottle is insured, with the closure disk under such tension as to resiliently retain itself in place in a general manner well known in connection with the ordinary bottle closure embodying merely a closure disk. This flexing will obviously be effected by providing the central portion of the die with its surface slightly lower than the marginal portion thereof so as to have contact with the central part of the closure immediately prior to engagement with the closure at the point 9 above the ring 8. It is further obvious that the spacer 16 will aid in preventing crushing or collapsing of the closure when piled within the hopper 14.

The closure disk 7 may be adhesively secured to the spacer 16 or to the ring 8, or both, or suitable staples or the like may be provided for such attachment. However, the ring 8 and spacer 16 are preferably glued or adhesively fastened to the underside of the top wall of the cap member 5 and have the closure disk 7 suitably fastened thereto. In each instance or form of the invention, the closure disk 7 is preferably provided with a peripheral locking projection or annular flange as at 17 adapted to engage the seat 11 in the mouth of the bottle 12. It will be apparent that the circular connecting member or ring 8, which is preferably of card board, is open at the center, thus leaving the major portion of the disk 7 free and unattached to the top wall of the cap member 5, whereby the disk 7 is capable of being readily flexed downwardly as mentioned above and illustrated in Figure 10. The pressure applied at 9 over the ring 8 is at a point within the

area of the opening of the milk bottle mouth, and the disk 7, being of slightly greater diameter than said opening, will be firmly seated and retained in place by the natural resiliency of the disk 7.

In the form of the invention shown in Figures 1 and 2, the depending part 13 consists of a central circular depressed portion of a relatively thin disk 18 secured at its margin to the undersurface of the marginal portion of the closure disk 7.

In the form of the invention shown in Figures 3 and 4, the depending part 13 is a circular central depressed portion of the disk member 7 itself, while in Figures 5 and 6, such depending parts consist in a plurality of studs 19 comprising small disks of cardboard secured by adhesive to and depending from the underside of the disk member 7. In the form of the invention shown in Figures 7 and 8, the construction is the same as shown in Figures 3 and 4, except that the projecting marginal portion 20 of the closure disk 7 is directed upwardly in the form of an annular flange encasing and secured to the outer periphery of the ring or connecting member 8. In the form of the invention shown in Figures 9 and 10, the construction is the same as shown in Figures 1 and 2, except that the depending part 13 comprises a relatively thick disk of pasteboard secured centrally to the underside of the disk member 7 and having a diameter considerably smaller than the latter.

Minor changes may be made without departing from the spirit and scope of the invention as claimed.

What I claim as new is:—

1. A bottle closure including a cap member embodying a substantially flat top wall having a depending rim, a closure disk spaced from and attached to the under side of said top wall, and a circular ring located between and having direct pressure contact with said top wall and the margin of said closure disk, said ring being adapted to transmit the pressure of a die from the contiguous portion of the top wall to the margin of said closure disk in the application of the closure to the bottle, said closure disk being provided inwardly of its margin with a depending portion located substantially in the same horizontal plane with the lower edge of the rim.

2. A bottle closure including a cap member embodying a substantially flat top wall having a depending rim, a closure disk spaced from and attached to the under side of said top wall, a circular ring located between and having direct pressure contact with said top wall and the margin of said closure disk, said ring being adapted to transmit the pressure of a die from the contiguous portion of the top wall to the margin of said closure disk in the application of the closure to the bottle, said closure disk being provided inwardly

of its margin with a depending portion located substantially in the same horizontal plane with the lower edge of the rim, and a spacing member located between and having direct pressure contact with the central portions of said top wall and said closure disk, said spacing member being spaced from said ring and adapted to transmit the pressure of the die from the center of the top wall to the center of said closure disk in advance of application of pressure to the margin of said closure disk for downwardly dishing the latter in the application of the closure to the bottle.

3. A bottle closure including a cap member embodying a substantially flat top wall having a depending rim, a closure disk spaced from and attached to the under side of said top wall, a circular ring located between and having direct pressure contact with said top wall and the margin of said closure disk, said ring being adapted to transmit the pressure of a die from the contiguous portion of the top wall to the margin of said closure disk in the application of the closure to the bottle, said closure disk being provided inwardly of its margin with a depending portion located substantially in the same horizontal plane with the lower edge of the rim, said closure disk having a peripheral portion projecting outwardly slightly beyond the periphery of said ring.

4. A bottle closure including a cap member embodying a substantially flat top wall having a depending rim, a closure disk spaced from and attached to the under side of said top wall, and a circular ring located between and having direct pressure contact with said top wall and the margin of said closure disk, said ring being adapted to transmit the pressure of a die from the contiguous portion of the top wall to the margin of said closure disk in the application of the closure to the bottle, said closure disk being provided inwardly of its margin with a depending portion located substantially in the same horizontal plane with the lower edge of the rim, said closure disk having a central depressed part forming said depending portion.

50 In testimony whereof I affix my signature.
JOHN EDDY CHACE.
